UNITED STATES PATENT OFFICE.

JOHN EDWARD COOPER, OF STRATFORD, LONDON, ENGLAND.

ANTIFRICTION MECHANISM AS APPLIED TO BOGIE-TRUCKS OF RAILWAY-CARS OR SIMILAR VEHICLES.

SPECIFICATION forming part of Letters Patent No. 764,428, dated July 5, 1904.

Application filed January 8, 1904. Serial No. 188,224. (No model.)

To all whom it may concern:

Be it known that I, JOHN EDWARD COOPER, a subject of the King of Great Britain and Ireland, residing at 9 Chatsworth road, Stratford, 5 London, England, have invented certain new and useful Improvements in Connection with Antifriction Mechanism as Applied to Bogie-Trucks of Railway-Cars or Similar Vehicles; and I do hereby declare the following to be a 10 full, clear, and exact description of the invention, such as will enable others skilled in the art to which it appertains to make and use the same.

This invention relates to antifriction mechanism as applied to the axle-shafts of bogie-trucks of railway-cars and similar vehicles; and it consists in new and improved combinations and arrangements of mechanism relating thereto.

According to this invention provision is made for combining with antifriction mechanism of the kind hereinafter described the usual or other suitably devised form of springs on which to mount the car or body of the vehicle, thereby reducing shocks and vibrations to a minimum, and thus obtaining a more perfect result from the antifriction mechanism by which the transmission is facilitated of heavier loads with reference to the power required to draw or propel them.

Having thus set forth the main object and utility of this invention, I will proceed to further explain the same by referring to the accompanying drawings, in which the car or passenger compartment or hold of the bogie-truck is entirely omitted as being unnecessary for the purpose of explaining the invention, and such outlines of the underframe as are shown are to be taken as representative of 35 bogie-trucks generally to which this invention is applicable in respect of those parts with which the antifriction mechanism is immediately connected.

Figure 1 illustrates in side elevation those parts of a bogie-truck in which the improvements constituting my invention are embodied, Fig. 2 being a half-plan view with the upper frame removed.

In the application of my invention to bogie-trucks the horn-plates a' are fixed in or form

part of the underframe a of the truck, but the guide-boxes b' and c' , with the axles b and c journaled therein, are free to slide up and down in the horn-plates in an exact relation to the movement of the springs d , and are thus 55 free from shocks or jolts which would be detrimental to the proper working of the antifriction mechanism. The main axle c is carried out beyond the hub of the wheel, so that the antifriction wheels or disks e , which are 60 provided in duplicate with the horn-plate a' between, as shown more especially in Fig. 2, are in rolling contact with the main axle on either side of the horn-plate journal-boxes b' and c' , which journal-boxes are accurately adjusted in the horn-plates a' to insure that they share the same vertical movement in conjunction with the provision that they be kept the same distance apart in all movements of the springs. 70

In this construction an equalizing-bar f is carried over or hooked onto the top of each split axle-box b' , by which means the weight is put onto the antifriction-axles b . A strap g is connected to the bottom side of the equalizing-bar, also to the outer ends thereof by means of screw-bolts both at the top and bottom, the bolts in the top end passing through angle-iron lugs h . By means of these angle-iron lugs and set-screws I am able to hold the 80 lower part of the top axle-box b' in the requisite position. In the bottom part of the strap g I provide two adjustable set-screws i , which are used to keep the bottom axle-box c' close up to the main axle c . By this means 85 I am enabled to keep the two axles b and c in rolling contact. The equalizing-bar f supports the whole weight of the vehicle, which may be mounted on springs d of a volute or spiral character at each end, as shown, or, if 90 necessary, elliptical springs may be arranged crosswise, the equalizing-bar passing over the top axle-boxes and hung inside the horn-plates. 95

What I claim, and desire to secure by Letters Patent of the United States, is—

1. In a truck, the combination of the frame provided with downwardly-extending horn-plates, a main and an antifriction axle journaled in each of said horn-plates, an equaliz- 100

ing-bar extending over such antifriction-
axles, and springs between said equalizing-bar
and said frame, substantially as described.

2. In a truck, the combination of the truck-
5 frame provided with downwardly-extending
horn-plates, bearings for a main axle and an
antifriction-axle located in each of said horn-
plates, a main and an antifriction axle, the
latter being provided with antifriction-wheels
10 bearing on said main axle, means for keeping
said axles in the proper relation to each other,
equalizing-bars passing over said antifriction-
axles, and springs between said equalizing-
bars and said frame, substantially as de-
15 scribed.

3. In a truck, the combination of a frame
provided with downwardly-extending horn-
plates, bearings for a main axle and for an an-

tifriction-axle located in each of said horn-
plates, a main axle and an antifriction-axle 20
journaled in said bearings, the latter being
provided with antifriction-wheels bearing
upon said main wheels, equalizing-bars pass-
ing over said antifriction-axles, springs be-
tween said equalizing-bars and said frame, 25
lugs and bolts for securing the bearing of said
antifriction-axles to said equalizing-bars, and
straps and adjusting-bolts for securing the
bearings of said main axles to said equalizing-
bars, substantially as described. 30

In testimony whereof I affix my signature in
presence of two witnesses.

JOHN EDWARD COOPER.
